BACKDRAFT DIVERTER

Frank B. Peters, Minneapolis, Minn.

Application March 21, 1938, Serial No. 197,108

2 Claims. (Cl. 126—307)

This invention relates to a draft hood or draft regulating device adapted to be used with a gas burning furnace or heater. Such draft hoods or regulators are now generally required in a furnace room where such a gas burning furnace or heater is used. The general functions of such a device are to insure the ready escape of the products of combustion in the event of no draft, back draft or stoppage beyond the draft hood, to prevent a back draft from entering the furnace or heater and to neutralize the effect of the stack action of the chimney flue upon the operation of the furnace or heater. It is one of said purposes to prevent an undue draft or puff of air from or through the chimney from blowing out the pilot light in said furnace or heater.

Such draft hoods or regulators thus have openings into the furnace room and in the devices previously used these openings have been located at a comparatively high point in the furnace room. There is a passage of air through these openings from the furnace room to the smoke pipe and chimney and this air is thus some of the warmer air in the furnace room. This passage of air thus tends to drain the heat or heated air from the furnace room. The air thus withdrawn must be replaced by cold air and the temperature of the furnace room is thus lowered.

It is an object of this invention to provide a draft hood or draft regulator which will accomplish all of the desired purposes of such a device and yet which will take any air which passes to the chimney therethrough from a point closely adjacent the floor of the furnace room. The coldest air in the furnace room is thus passed up the chimney and the warmer air some distance above the floor is conserved so that a higher temperature is maintained in the furnace room.

It is a further object of the invention to provide a draft hood or draft regulator of very simple, inexpensive and easily installed form.

It is still another object of the invention to provide a draft hood or draft regulating device which can be easily inserted in the conduit leading from the furnace to the chimney, said device having lateral extensions adapted to be connected respectively to the furnace and chimney and adapted to have a conduit extending therefrom to the floor of the furnace room.

These and other objects and advantages of the invention will be fully set forth in the following description made in connection with the

accompanying drawing in which like reference characters refer to similar parts throughout the several views and in which:

Fig. 1 is a view in side elevation of a furnace, a portion of the chimney, the smoke pipe connecting the same and the device of the invention connected thereto;

Fig. 2 is a view in side elevation of a draft hood embodying the present invention, some parts being broken away;

Fig. 3 is a vertical section taken on line 3—3 of Fig. 4 as indicated by the arrows;

Fig. 4 is a horizontal section taken on line 4—4 of Fig. 3 as indicated by the arrows; and

Fig. 5 is a horizontal section taken on line 5—5 of Fig. 2 as indicated by the arrows.

Referring to the drawing in Fig. 1 a furnace designated generally as 10 is shown which will be equipped with suitable gas burning apparatus. While the type of furnace indicated is of the hot air type having the air outlet conduits 10a it will be understood that any type of gas burning furnace or heater may be used with the invention. Furnace 10 is shown as having a smoke pipe connection 10b to which is connected smoke pipe 11. Smoke pipe 11 as shown, extends upwardly and then horizontally in line with the connection 12 into the chimney 13 or into the flue thereof. The draft hood or draft regulator constituting the present invention comprises a member 14. Member 14 has a central portion 14a and while this portion might have various shapes, in the embodiment of the invention illustrated it is shown as substantially cylindrical and as having a closed top 14b. Portion 14a has a chamber therein and conduit portions 14c and 14d project from either side thereof, the same having flaring portions 14e and 14f respectively extending to the sides of member 14 and suitably connected thereto in any suitable manner as by welding. It will be noted that the sides and bottom parts of portions 14e and 14f extend generally downward. Portion 14a has top wall portions 14g therein which extend from opposite sides respectively downwardly toward the center of said portion where they meet and then extend downwardly in a vertical plane centrally of member 14 to form a baffle plate 14h. It will be noted that baffle 14h extends downwardly a short distance below the connecting portions 14e and 14f. A conduit 15 is connected to the bottom of member 14 and extends to or substantially to the floor of the furnace room in which the furnace or heater 10 is disposed. The conduit 15 has formed therein and extending

thereinto closely adjacent said floor a plurality of openings 15a. When the device is installed as shown in Fig. 1, portion 14c is connected to the furnace by smoke pipe 11 and portion 14d is connected to the chimney by smoke pipe 11.

In operation, the products of combustion from the gas burner in furnace or heater 10 will pass out through the portion 10b and through the smoke pipe 11 which is connected to portion 14c as shown in Fig. 1. These products of combustion must then pass downwardly around the lower end of baffle plate 14h which extends across portion 14a as shown in Fig. 4. Said products then pass upwardly and through portion 14d to smoke pipe 11 and to the chimney. This path of travel is indicated by the arrows in Fig. 3. Should there be an excessive or sudden draft through the chimney, air will be drawn in the conduit 15 through the openings 15a therein. The baffle 14h prevents a direct draft or pull through portion 14c and the furnace, and the gas burner and especially the pilot thereof is shielded from any such sudden draft through the chimney. This is particularly important when the pilot is burning and the main burner is not burning. It frequently happens that there is a sudden back draft through the chimney and should this occur the air would pass back through portion 14d and would be intercepted by the baffle 14h and be relieved through the openings 15a. The baffle 14h in this case would shield the gas burner and pilot and prevent any puff back into the furnace or heater. Should any stoppage occur in the smoke pipe beyond member 14 the products of combustion could still escape through conduit 15 and the openings 15a so that an excessive pressure could not be created in the furnace or heater.

The member 14 can be made either from light cast iron or from sheet metal. Most regulations require that the thickness be at least equal to No. 26 U. S. standard gage sheet steel. The parts must be so connected that they will withstand a temperature of 1000 degrees F. without melting, softening or distortion of any part. It is desirable that the area of the conduit 15 be substantially equal to the combined areas of conduit portions 14e and 14d.

From the above description it will be seen that I have provided a simple and very efficient construction of a draft hood or draft regulator for a gas burning furnace or heater. The device could be cheaply made and it is quite easily installed in the standard smoke pipe. In the use

of said device the air which passes from the furnace room out through the chimney and through the device is taken from a point very close to the floor of the furnace room. This air will be the coldest air in the furnace room. The warmer air at higher levels will thus be retained and conserved and the temperature of the furnace room can be maintained at a much higher point than if the warm air were taken therefrom. The inlet and outlet portions 14c and 14d are of the same size as the smoke pipe 11 used on the furnace or heater. The flaring portions 14e and 14f insure a full capacity for the gases and an easy flow through the hood or diverter. It will thus be seen that any back draft will be diverted into conduit 15 and dissipated through openings 15a. As stated, any unusual draft through the chimney will also be relieved by drawing air through openings 15a so that all danger of extinguishing the pilot light is eliminated. The device has been amply demonstrated in actual practice and found to be very successful and efficient.

It will, of course, be understood that various changes may be made in the form, details, arrangement and proportions of the parts, without departing from the scope of applicant's invention, which generally stated, consists in a device capable of carrying out the objects above set forth, in the parts and combinations of parts disclosed and defined in the appended claims.

What is claimed is:

1. A draft hood or regulator for a gas furnace or heater in a furnace room comprising a hood having a central portion with a closed top, conduit portions extending laterally from said central portion a short distance below said top and having downwardly extending sides and bottoms connected to said central portion, said conduit portions being adapted for connection respectively to said furnace or heater and to a chimney, a vertically extending baffle plate extending across said central portion between said laterally extending portions and for some distance below the latter, a conduit connected to the bottom of said central portion and extending to the floor of said furnace room, said last mentioned conduit having openings therein adjacent said floor through which cold air may enter and pass to said chimney.

2. The structure set forth in claim 1, said central portion having walls sloping from each side of its top downwardly to said baffle plate.
